FLOAT TROWEL FOR CEMENT
FLOOR FINISHERS

Marvin Edwin Whiteman, Los Angeles, Calif.

Application April 12, 1948, Serial No. 20,385

3 Claims. (Cl. 94—45)

1

This invention relates to a float trowel for cement floor finishers and may be regarded as an improvement over a construction disclosed in my prior U. S. Letters Patent No. 2,198,929, issued April 30, 1940.

In the above numbered patent there is disclosed a cement floor finisher wherein three radially extending finish trowels are rotatably mounted about a vertical central axis and are adapted to be driven by a suitable source of power. A handle is secured to the device to facilitate its being manipulated over the surface of a cement floor that is to be finished and by means of an adjustment the tilt of the trowels can be adjusted while they are being rotated about the vertical central axis so as to cause them to impart the desired finish surface to the concrete.

Preparatory to finishing a cement or concrete floor it is desirable to perform a so-called "floating" operation wherein a relatively broad trowel is worked in a flat condition over the wet cement to prepare the cement for the finishing operation. In the course of this floating operation the fines are effectively worked to the surface and the cement is otherwise advantageously prepared for the finishing operation.

While the finish trowels disclosed in the above mentioned patent are capable of assuming flat or unilted positions with relation to the cement floor, they are generally unsuitable for performing the floating operation due to the fact that they are relatively narrow and their side edges are seldom if ever turned upwardly. Consequently if the finish trowels were used for the floating operation there would be always a tendency for the trowels to dig into the wet cement in the course of their rotation about the vertical central axis.

An object of the present invention is to provide a float trowel which may be applied over the finish trowels of a cement floor finisher of the general type disclosed in the above numbered patent. In this manner, on applying the float trowels to the machine the finisher may be easily and quickly converted to a floating machine. The trowels may be of adequate breadth and may have all of their side edges bent upwardly so as to avoid digging into the wet cement while the trowel is rotated about the vertical central axis in a flat position. After the cement has been "floated" the float trowels can be easily and quickly removed from the finish trowels thus converting the machine into a finishing machine and the finishing operation may then be performed.

Another object of the invention is to provide

2

a cement floor finisher which is so constructed that it may be easily and quickly converted from a floating machine into a finishing machine, or vice versa.

5 A further object of the invention is to provide a float trowel that is applicable to the finish trowel of a cement floor finisher which will remain in position when applied thereto but which can be easily and quickly removed.

With the foregoing and other objects in view, which will be made manifest in the following detailed description and specifically pointed out in the appended claims, reference is had to the accompanying drawings for an illustrative embodiment of the invention wherein:

Figure 1 is a top plan view of a cement floor finisher of the type disclosed in my prior patent but illustrating the float trowels embodying the present invention as having been applied thereto;

Fig. 2 is a perspective view of one of the float trowels embodying the present invention in a position wherein it is about to be applied to one of the finish trowels of the cement floor finisher;

Fig. 3 is a vertical section taken substantially upon the line 3—3 upon Fig. 1; and

Fig. 4 is a sectional view taken substantially upon the line 4—4 upon Fig. 3.

Referring to the accompanying drawings wherein similar reference characters designate similar parts throughout, the cement floor finisher illustrated in Fig. 1 is of the general type disclosed in my prior patent wherein there is a suitable source of power such as an electric motor 10 supplied with current through a cord 11 and which is mounted on a gear box 12. This gear box serves to drive a vertical shaft, not shown, which rotates a plate 13 on which a plurality of radially-extending equally spaced bearings 14 are mounted. These bearings serve to rotatably support the inner ends of the bars 15 which in turn are detachably secured such as by cap screws 16 to bars 17 on the backs of finish trowels 18. Outer bars 19 are also secured to the bars 17 and provide recesses that pivotally receive pins 20 which are at equally spaced intervals on a ring 21 that is concentrically arranged around the plate 13. A handle 22 is secured to the gear box and assists at facilitating the manipulation of the machine over the surface of the cement floor to be finished. A knob 23 that is mounted on the handle serves on rotation to adjust a thrust collar on the vertical shaft which is engageable with arms on the inner ends of the bars 15 that are disposed on the inner ends of the bearings 14. Consequently, by rotating the knob 23 the in-

clination or tilt of the finish trowels 18 may be simultaneously adjusted while they are being rotated about the vertical central axis in the course of imparting a finish surface to the cement floor. The above described construction is the same and is disclosed in further detail in my prior patent referred to above.

While the finish trowels may have their outer and inner ends bent upwardly slightly, as indicated at 25 and 26, the side edges 27 and 28 are 10 not so bent. This is particularly true of the trailing edge 27 which imparts the smooth finish surface to the floor as the trowels are moved thereover. The finish trowels also are usually relatively narrow, as illustrated in Fig. 2, and because of their size and the lack of the upturned side edges the finish trowels are unsuitable for performing the floating operation even though the trowels may be adjusted by the knob 23 to assume perfectly horizontal positions.

The float trowel embodying the present invention consists of a relatively broad section of sheet metal 29 which not only has its ends bent upwardly as indicated at 30 and 31 but also has the side edges bent upwardly as indicated at 32 and 33. A cap 34 extends from end to end of the float trowel and may be spot welded thereto as indicated at 35 adjacent the leading edge 32. This cap extends from adjacent the leading edge toward the trailing edge 33 so as to substantially cover over the forward half of the finish trowel when the float trowel is applied thereto. The ends of the cap may be bent downwardly, as indicated at 36, over the upwardly bent ends 30 and 31 of the finish trowel. In this manner the cap 34 cooperates with the body of the float trowel to form a rearwardly open pocket designed to receive approximately the forward half of the finish trowel. A spring clip 37 may be secured to the top of the cap such as by spot welding 38 and this spring clip is formed with a detent 39 adapted to be snapped over the bar 47 on the finish trowel to retain the float trowel in position.

When float trowels constructed as above described have been applied to the finish trowels on the machine, the machine may be operated in very much the conventional manner except that the knob 23 is adjusted so that the finish trowels and consequently the float trowels thereon will assume perfectly horizontal positions which are required in performing the floating operation. As the float trowels have upwardly bent side edges, particularly the leading edge 32, there is no tendency of the float trowels to dig into the wet cement in performing the floating operation. Furthermore, as the float trowels have their pockets open rearwardly and are applied over the leading edge 29 of the finish trowels, there is very little danger or tendency for the float trowels to become displaced from the finish trowels. In many instances the retaining spring clip 37 may be unnecessary due to the fact that the drag on the float trowels in the course of their movement tends to push the float trowels onto the finish trowels.

When the floating operation is completed the spring clips 37 may be sprung upwardly to release the float trowels and they may be easily and

quickly removed. This exposes the bottom surfaces of the finish trowels and the machine may then be used in the manner disclosed in my prior patent to perform the finishing operation in the usual manner.

From the above described construction it will be appreciated that by the use of the float trowels embodying the present invention a cement floor finisher may be easily converted into a floating machine and on removal of the float trowels the finisher may be restored to a machine designed to perform the finishing operations on the cement.

Various changes may be made in the details of construction without departing from the spirit and scope of the invention as defined by the appended claims.

I claim:

1. A float trowel for cement floor finishers comprising a rectangular section of sheet metal having its edges bent upwardly, means providing a three-sided rearwardly open pocket on the back of the section adjacent the leading edge thereof adapted to partially receive a finish trowel of the finisher, and a spring clip secured to the top of the pocket-forming means and extending rearwardly therefrom so as to be engageable with the finish trowel to retain the section thereon.

2. In combination with a cement floor finisher having one or more finish trowels mounted for rotation thereon and adapted to be moved over a floor to be finished, corresponding float trowels underlying the finish trowels, said float trowels having rearwardly open pockets formed thereon adjacent the leading edges thereof partially receiving the finish trowels, and means on the float trowels for releasably retaining the float trowels on the finish trowels.

3. A float trowel for cement floor finishers comprising a rectangular section of sheet metal having its leading edge and its side edges bent upwardly, means providing upright surfaces on the upper side of said section arranged to engage the leading edge and the end edges of a finish trowel of a cement floor finisher so that said section can be held against lateral displacement with respect to the finish trowel by said surfaces, and a rearwardly extending spring clip secured to said section extending rearwardly over the upper surface of said section so as to be engageable with the finish trowel to retain said section thereon.
